UNITED STATES PATENT OFFICE

AINSLIE T. CARTER, OF ALBANY, NEW YORK, ASSIGNOR, BY MESNE ASSIGNMENTS,
TO GENERAL RAILWAY SIGNAL COMPANY, A CORPORATION OF NEW YORK

ELECTRICAL CONTACT

Application filed November 6, 1922. Serial No. 599,187.

My invention relates to electric contacts and particularly to contacts used in relay and other devices for controlling the opening and closing of electrical circuits. I will describe 5 one form of electric contacts embodying my invention, and will then point out the novel features thereof in claims.

In the accompanying drawing, Fig. 1 is a view partly in side elevation and partly in 10 vertical section of two electric contacts embodying my invention with which a controller arm alternately engages. Fig. 2 is a sectional view on the line 2—2 of Fig. 1.

Similar reference characters refer to similar parts in each of the views.

In the drawings I have illustrated my invention as being applied to a relay device, such as is commonly used for controlling the 20 operation of railway signaling devices. The relay is shown as comprising a top plate 1 of insulating material such as porcelain and serving as a support, a bottom plate 30, and glass side walls 31, separated from the top and bottom plates by gaskets 33. The top 25 and bottom plates are spaced by the side walls and by corner posts which are not shown in the drawings, and are held together by screws 32, one only of which is shown in the drawing.

30 Mounted in the top plate 1 is an electromagnet, designated as a whole by the reference character A, and comprising, as usual two windings, 2, 2, surrounding cores 2^a, 2^a, which cores project through the top plate 1 and terminate in pole pieces 3, 3, resting against the underside of the top plate. The electromagnet A controls an armature 5 constituting a controller arm which is pivotally mounted at 6 in any desired manner. The 35 controller arm 5 engages a front contact 8 to control one circuit and a back contact 9 to control another circuit. In the drawings I have shown only one front and one back contact and one finger or arm F, but in accordance with the usual practice, and especially in relay practice there will be a number of such contacts and controller arms each behind the other as viewed in Fig. 1.

40 The contact member 8 in the form here shown, is of carbon and conical in shape, and

is supported in a tubular shell 8^a of electro-conductive material, the inner surface of which is likewise conical in formation. In assembling these parts the carbon member or button is pushed into the shell so that any strain which is put into the carbon button is distributed over the whole conical surface of this member. The carbon button is held in position in the shell 8^a by placing on top of this button a cylindrical block 8^b which fits the shell snugly, this block being pressed in until it rests on the carbon button and so holds the latter firmly in position in the shell. The assembly is finished by spinning or pressing the upper rim of the shell 8^a over the block 8^b. The block 8^b is provided with a threaded hole to receive a threaded terminal post 8^c by means of which the contact is supported, (in this instance the top plate 1) whereby the vertical position of the carbon button 8 may be adjusted by turning the shell 8^a on the post. This shell is locked in adjusted position by means of a nut 19 on the post 8^c.

55 The back contact 9 comprises a contact plate 9^a preferably of silver or other suitable material, attached to a contact spring 15. This spring 15 is made of high grade non-corroding spring material such as phosphor bronze, and is riveted at 16 to a comparatively rigid arm 17. The outer or free end of the spring 15 is bent downwardly and provided with a slot a which receives, with considerable clearance, the adjacent end of the arm 17, as best shown in Fig. 2. The end of the spring 15 normally tends to engage the under surface of the arm 17; that is to say, the normal bias of the spring is such as to cause the spring to move away from the arm 17 as far as permitted by the vertical limits of slot a. In other words, spring 15 is assembled with an initial trapped upward pressure. When the magnet is de-energized so that the contact finger F engages the plate 9^a, the spring 15 will be depressed until the weight of the armature and the parts carried thereby is balanced. Then when the magnet becomes energized the spring 15 will follow the movement of the armature and of contact tip 9^a to an extent limited by the slot a. It will 60 be seen, therefore that the back contact spring

15 exerts a definite lifting force on the armature, tending to assist the armature in its upward movement until the spring 15 is arrested by the arm 17. As here shown the 5 arm 17 is bent backwardly on itself and the lower right hand end is attached to a bracket 41 at its bent end 41', which bracket in turn, is mounted in a terminal post 42 suspended from a support and as here shown by the top 10 plate 1. An adjusting screw 18 is provided with a locknut 18^a and passes through the smooth bored end of bracket 41 and the threaded bored lower end of the arm 17, to engage the upper portion of this arm where- 15 by the exact desired position of the contact spring 15 may be secured during adjustment and calibration of the relay by adjusting the screw 18 and thus raising or lowering, as a unit, the spring 15 and upper leg of arm 17. 20 The structure described hereinbefore for mounting the carbon button 8 has several important advantages among which are the following: A comparatively large contact area exists between the carbon button 8 and 25 the shell 8^c. The lower surface of the contact button i. e. the surface which is presented to the tip 12, is rounded or spherical in formation so that slight inaccuracies in the alignment of the tip 12 will not affect the contact 30 between this tip and the button 8. The vertical adjustment of the button 8 can be carried out to a very fine degree of accuracy by screwing this member up and down on the terminal post 8^c to any fraction of a turn. 35 The shell 8^c is kept in tension, thus maintaining pressure between this shell and the carbon button, and so maintaining a good contact between the two.

The construction of the back contact 9 40 overcomes certain difficulties which have heretofore been encountered in back contact construction, and provides for adjustment as hereinbefore explained. One feature of this contact is that the spring member 15 is of 45 generous size, so that it can be easily handled without damage, and of such shape that its spring pressure is not subject to change due to changes in internal stresses of the material which may be caused by bending during 50 fabrication. It will be noted that this spring member 15 has but one bend, which bend is 90°, so that even if the stresses at this bend should change, the bent portion, that is, the vertical portion will change its relative position but very slightly. It will be noted that 55 the vertical portion has a rectangular hole α which receives the end of the arm 17, the purpose of this construction is to obtain a back contact which is restrained in both its 60 up and down movement. By virtue of this design it is possible to trap an initial pressure in the spring 15 without putting a permanent bend in the horizontal portion of the spring, this being done by merely over-bending or 65 under-bending the arm 17 as may be desired;

in other words, a slight bend is put into spring 15, which bend, however, does not cause a permanent set in the spring material as the stresses in this member may easily be kept below the elastic limit. The contact 70 plate on this spring is a silver rivet which can easily be inserted in a small hole punched in the spring, so that no soldering operation at this point is required, and, consequently, there is no danger of drawing the temper of 75 the spring. The size of the spring is such that the riveting operation can easily be performed without destroying the spring. A soldering operation may be desirable at the rivet 16, that is, at the extreme right hand end of the spring 15, but if so it will be noted that the point where the solder is applied is outside of that portion of the member which acts as a spring, so that it is 80 extremely unlikely that poor soldering or high temperature will affect the resilient characteristics of the spring as a whole. By means of the screw 18 and the shape of the arm 17 the contact is adjustable without changing the pressure trapped in the spring 85 90; in other words, after assembling the contact in the relay the position of the contact plate 9 may be adjusted either up or down without changing the pressure originally trapped in the spring 15, thus providing a 95 feature, which, as will be well understood, is highly desirable.

What I claim as my invention is:

1. A contact structure comprising a movable member pivoted at one end and provided 100 with a contact element at the other end, a flexible contact spring coacting with said member and biased to move toward said member, and means for limiting the movement of said contact spring toward said member comprising a relatively stiff arm passing through an opening in the end of said contact spring.

2. A flexible contact spring biased to move 110 in one direction, a relatively rigid supporting arm for said spring having a portion thereof passing through an opening in said spring and limiting the movement of said spring in its biased direction, and means for positively adjusting the position of both the spring and the arm without changing their 115 relative positions or tensions.

3. A contact structure comprising a mov- 120 ably mounted contact element, a supporting arm mounted adjacent said element, a flex- 125 ible contact spring mounted on said arm and having a natural bias toward said element, means associated with the arm and spring for limiting the motion of said spring toward said element, and means for simultaneously and positively adjusting the position of both said arm and said spring relative to said ele- 130 ment without affecting the bias of the contact spring.

4. A contact structure comprising a mov-

ably mounted contact element, a supporting arm mounted adjacent said element, a flexible contact spring mounted on said arm and having a natural bias toward said element, means associated with the arm and spring for limiting the motion of said spring toward said element, and means for flexing said supporting arm to simultaneously and positively adjust the position of said arm and said spring relative to said element without changing the bias of said spring.

5 5. A contact structure comprising a movably mounted contact element, a supporting arm mounted adjacent said element, a flexible contact spring mounted on said arm and having a natural bias toward said element, a relatively rigid extension on said arm limiting the motion of said spring toward said element, and means, incapable of varying 10 the bias of said contact spring, for positively and simultaneously adjusting the position of said arm and said spring relative to said element.

6. A contact structure comprising a movably mounted contact element, a supporting arm mounted adjacent said element, a flexible contact spring mounted on said arm and having a natural bias toward said element, an extension on said arm limiting the motion of 15 said spring toward said element, and means for flexing said supporting arm to simultaneously and positively adjust the position of said arm and said spring relative to said element.

35 7. A support, a relatively rigid arm connected at one end to the support, a flexible member carried by the arm and biased to move in one direction, means for adjusting the position of the free end of the arm and the said member without disturbing their 40 relative positions, and means associated with the arm and member for limiting motion of the flexible member.

8. In a contact structure, a support, a relatively rigid arm connected to said support, a 45 flexible member fixed to an intermediate part of said arm and having its free end spaced, and biased away, from said arm, a down-turned loop on the flexible member sleeving 50 the free end of said arm, and an adjusting screw carried by said support and having its inner end bearing against said arm inwardly of the point where said arm and member are spaced apart.

55 In testimony whereof I affix my signature.
AINSLIE T. CARTER.
